UNITED STATES PATENT OFFICE.

FREDERICK H. LATHROP, OF CHICAGO, ILLINOIS, ASSIGNOR OF ONE-HALF TO JOHN J. McCARTHY, OF CHICAGO, ILLINOIS.

ROTARY ENGINE.

No. 874,775.

Specification of Letters Patent.

Patented Dec. 24, 1907.

Application filed March 24, 1905, Serial No. 251,707.

To all whom it may concern:

Be it known that I, FREDERICK H. LATHROP, a citizen of the United States, residing at Chicago, in the county of Cook and State 5 of Illinois, have invented a new and useful Improvement in Rotary Engines; of which the following is a specification.

My invention relates particularly to rotary engines adapted to use gas or oil for motive 10 purposes.

My primary object is to provide a simple and durable engine of the character indicated capable of economical operation.

The invention is illustrated in its preferred 15 embodiment in the accompanying drawings, in which—

Figure 1 is an end elevational view of my improved engine, the admission and exhaust valves being shown in section, however; Fig. 20 2, a vertical section taken as indicated at line 2 of Fig. 1; Fig. 3, a transverse section taken as indicated at line 3 of Fig. 2; Fig. 4, a horizontal section taken as indicated at line 4 of Fig. 3; Fig. 5, a broken vertical section 25 taken as indicated at line 5 of Fig. 1, showing details of the admission valves; Fig. 6, a broken section taken at line 6 of Fig. 1 and showing details of the exhaust valves; and Fig. 7, an enlarged broken section taken as 30 indicated at line 7 of Fig. 5.

It may be preliminarily stated that the drawings show an engine equipped with two annular chambers in which move piston members separated by an angle of 180°, and 35 that, as the parts are timed in the construction illustrated, the following cycle of operations occurs at each half of the engine, though at different times, viz.: First, the charge is drawn in and air expelled; second, the charge 40 is compressed and air drawn in; third, the charge is exploded and air expelled; and fourth; the products of combustion are expelled and air drawn in to cool the cylinder. During the explosion at one side of the engine 45 compression occurs at the other side in the preferred arrangement.

In the construction shown, A represents an engine casing which may be supported in any suitable manner, the casing comprising 50 detachably connected sections A¹ A²; B, a rotary shaft having fixedly secured thereon disks B¹ B² equipped, respectively, with piston members B³ B⁴ moving in annular chambers B⁵ B⁶, respectively; C C¹, rocking valves

or abutments adapted to swing across the 55 annular chambers and afford, for the time being, stationary abutments against which the pressure can act; C² C³, rods serving to actuate the members C C¹, said rods being actuated by cams C⁴ C⁵ carried by the shaft 60 B; D D¹, admission valves, controlled, respectively, by cams D² D³; E E¹, exhaust valves controlled, respectively, by cams E² E³; F F¹, shafts serving to actuate the cams D² D³, E² E³; F² F³, worm-wheels mounted on 65 said shafts and actuated by worms F⁴ with which the ends of the shaft B are equipped; and G G¹, portions of electric circuits connected with sparking plugs G² G³, of well-known construction.

The frame and casing-section A¹ is provided, with a chamber for the valve C, and this chamber has a removable top-section a; and the casing-section A² is provided with a corresponding chamber for the valve C¹ 75 which is equipped with a removable section a¹. The shaft B is supported in bearings a² a³, and each casing section has an annular wall a⁴ which forms the inner wall of the corresponding annular chamber. Sufficient 80 space is left between the walls a⁴ to permit the disks B¹ B² to rotate freely with the piston members with which they are equipped. The casing is chambered as indicated at points a⁵ to enable water or air to be circulated for cooling purposes.

The piston members B³ B⁴ are firmly secured to the peripheral portions of the disks B¹ B², as by means of screws and lugs b. Each of said members is hollow and of suitable curved form to move in the annular chamber in which it is confined. Each of said members is equipped at its front end with a spring-held inwardly opening valve b¹, and each member has at the rear portion 95 of its lower or inner concave wall an outlet passage b², which registers, in one position of the piston member, with a passage b³ formed in the adjacent surface of the corresponding annular casing member a⁴. Each piston member is provided in advance of the valve b¹ with an end having perforations b⁴ through which gas is admitted during the compression stroke.

Each of the rocking abutments C C¹ constitutes a portion of a cylinder, a portion of the cylinder being cut away at the line c, so that when the abutment is in one position

the piston member can pass freely under it. Each rocking abutment is equipped with a stub-shaft c^1 with which the corresponding one of the actuating rods $C^2 C^3$ is connected.

5 Each of the admission valves $D D^1$ comprises a valve-casing d formed with a pipe d^1 communicating with the corresponding annular chamber of the engine and controlled by a check-valve d^2 ; a vertically movable plunger d^3 equipped with valves $d^4 d^5$; an oil-admission pipe d^6 connected with the upper portion of the casing; and an air-admission pipe d^7 communicating with the upper portion of the casing. The casing is formed

10 with a central chamber d^8 with which the pipe d^1 communicates, and this chamber is separated from upper and lower chambers $d^9 d^{10}$ by valve seats $d^{11} d^{12}$, respectively. The valve d^4 is located beneath the valve seat

15 d^{12} and the valve d^5 is located above the seat d^{11} . When either valve is fully open the other is closed. As shown in Figs. 1 and 7, the pipe d^8 communicates, through a passage d^{13} with a chamber d^{14} formed in the upper

20 end of the casing and into which the upper end of the plunger d^3 extends. From the upper portion of the chamber d^{14} leads a passage d^{15} which communicates with the chamber d^9 adjacent to the point of connection with the pipe d^7 . The chamber d^{10} is in communication with the atmosphere through passages d^{16} . The plungers d^3 are actuated by slides d^{17} arranged in suitable guides and actuated by the cams $D^2 D^3$. It will now

25 be understood that when the plunger d^3 is depressed, as shown in Fig. 5, air may be drawn into the cylinder of the engine through the passages d^{16} , the oil in the meantime being allowed to collect in the

30 chamber d^{14} ; and when the plunger d^3 is raised the admission through the passages d^{16} is checked and air drawn in through the pipe d^7 , a mixture being formed with the oil which is sprayed from the passage d^{15} by the

35 rising plunger. At each revolution of the piston, a charge of explosive mixture or a charge of air is drawn into the cylinder past the check-valve d^2 , depending upon the position of the valves $d^4 d^5$.

40 Each of the exhaust valves $E E^1$ comprises a casing e connected by a pipe e^1 with the corresponding annular cylinder of the engine; and a vertically movable valve e^2 actuated by a slide, or plunger, e^3 engaging

45 the appropriate one of the cams $E^2 E^3$. The final discharge is through a pipe e^4 communicating with the valve chamber beneath the valve e^2 . The exhaust valves are timed so that they remain open excepting during

50 the periods when the piston members are compressing the charges of explosive mixture.

55 As shown, the shafts $F F^1$ are arranged beneath the extremities of the shaft B and perpendicular to the shaft B . The construc-

tion will be understood without further detailed description. The shafts $F F^1$ are timed to raise the plungers d^3 of the admission valves once in four revolutions, although, as will be readily understood, the parts may be so timed that said plungers will be raised once in every three revolutions, making the engine a three-cycle engine instead of a four-cycle engine, if so desired.

The electric circuits $G G^1$ may be arranged in any suitable manner. As shown, each comprises a stationary contact member g and a movable contact member g^1 , the movable contact members being actuated at proper intervals by the cams $D^2 D^3$.

No special provision for packing between the casing and piston members is shown, but any suitable packing may be employed.

The operation will be readily understood. With the parts timed as shown in the drawings, the engine is a four-cycle double engine providing for compression at one cylinder during the working stroke at the other cylinder. At either cylinder, the cycle of operations is as follows, viz: First, a charge of explosive mixture is drawn in, and air expelled, the cam-actuated admission valve being raised and the exhaust valve open; second, the charge of explosive mixture is compressed and air drawn in in the rear of the piston member, the cam-actuated admission valve being lowered and the exhaust valve closed; third, the charge is exploded, the check-valve at the admission closing, and air is expelled from in front of the piston member, the exhaust valve being open; and fourth, the burned gases are discharged and air drawn in in the rear of the piston, the cam-actuated air admission valve remaining depressed and the exhaust valve being open. In the operation of compressing the charge, the mixture forces the valve b^1 of the hollow piston member open and enters the hollow piston member, the rocking abutment being, during this operation, in the position shown in Fig. 3 and the exhaust valve being closed. The rocking abutment is actuated at each revolution of the main shaft, rising out of the annular cylinder long enough to permit the piston member moving therein to pass. At the time that the firing takes place, the piston member is in the position shown by full lines in Fig. 3, so that the charge can escape to the rear side of the piston member and propel the latter. Some of the burned gas remains in the piston member until the revolution succeeding the explosion, when it is practically exhausted and mixed with the air which is drawn in during the revolution succeeding the working stroke. The use of the engine as a four-cycle engine, instead of a three-cycle engine, is preferred for the reason that it enables the burned gas in the piston member to be thus disposed of and also enables the cylinder to be properly cooled. If

preferred, however, the engine may be employed as a three-cycle engine, as stated above.

It will be understood that many changes in details of construction within the spirit of my invention may be made, hence no undue limitation should be understood from the foregoing detailed description.

What I regard as new, and desire to secure 10 by Letters Patent, is—

1. In a rotary engine, the combination of a cylinder, a rotary piston-member having a chamber for explosive mixture and a valveless exit passage, and a valve controlling the 15 admission to said chamber, for the purpose set forth.

2. In a rotary engine, the combination of a cylinder, a rotary piston-member having a chamber for compressed explosive mixture 20 and equipped with a valve controlling the admission to said chamber said chamber having a valveless exit passage, and admission and exhaust valves for the engine, for the purpose set forth.

25 3. In a rotary engine, the combination of a cylinder, a rotary piston-member having a valved chamber for explosive mixture, an exhaust valve, and admission means comprising a spring-held check-valve, a cam- 30 actuated rod, valves on said rod controlling separate fuel and fuel and air admission passages, for the purpose set forth.

4. In a rotary engine, the combination of a cylinder, a valved hollow piston-member 35 movable therein, an exhaust valve, a suitably actuated abutment movable into said cylinder, and admission means comprising a passage equipped with a check valve, a valve-casing connected therewith and provided with two valve-seats and having air- 40 admission passages on opposite sides of said valve-seats, an oil-chamber having a passage opening into the valve-casing adjacent to one air inlet thereof, a plunger projecting 45 into the oil-chamber and serving to eject the oil, and valves on said plunger coating with said valve-seats, for the purpose set forth.

5. In a rotary engine, the combination 50 of a casing provided with an annular chamber having a recess in one wall thereof and an admission port adjacent to said recess, a valved hollow piston-member movable in said annular chamber and provided with an opening registering with said recess during 55 a part of the movement of the piston-member, a movable abutment adapted to enter the annular chamber, and admission and exhaust controlling means, for the purpose set forth.

60 6. In a rotary engine, the combination of a rotary shaft equipped with a disk, a valved hollow piston member projecting laterally from the disk near the periphery thereof, a casing having an annular chamber in which 65 said piston-member is movable and which

has one of its walls provided with a recess, said piston-member having an opening registering with said recess in one position of the piston-member, a movable abutment adapted to enter said annular chamber, and 70 suitably actuated admission and exhaust valves, for the purpose set forth.

7. In a rotary engine, the combination of a casing provided with two adjacent annular chambers, a disk separating said chambers, 75 valved hollow piston-members attached to and flanking said disk and separated from each other by an angle, said piston-members being movable in said annular chambers with said disk, movable abutments adapted 80 to enter said annular chambers, and admission and exhaust valves for the annular chambers, for the purpose set forth.

8. In a rotary engine, the combination of a shaft equipped centrally with a disk, valved 85 hollow piston-members attached to and flanking said disk, casing sections in which said shaft is journaled and which flank said disk and are provided with annular chambers in which said piston-members are 90 movable, a pair of movable abutments adapted to enter said annular chambers, and suitably actuated admission and exhaust valves, for the purpose set forth.

9. The combination of a casing formed 95 with two annular chambers therein, a disk separating said chambers, a shaft journaled in the casing and having said disk secured thereon, valved hollow piston-members flanking said disk and movable in said annular chambers, rocking abutments adapted to enter said annular chambers and each having a shaft projecting through one end of the casing, cams on said first-named shaft connected with the shafts of the rocking abut- 100 105 ments, admission and exhaust valves for the annular chambers, and transverse shafts geared to said first-named shaft and serving to actuate said admission and exhaust valves, for the purpose set forth.

10. In a rotary engine, the combination with a cylinder and a rotary piston, of admission means comprising an admission passage equipped with a check-valve, a casing having a central chamber in communication with said passage, and chambers above and below said central chamber and separated therefrom by valve-seats, a fuel-chamber in the upper portion of said chamber and provided with a discharge orifice opening 110 115 into the upper chamber, a plunger controlling said fuel-passage, and a pair of valves carried by said plunger and located, one above the upper valve-seat and the other below the lower valve-seat, the valves being spaced so that when either valve is closed the other is open, for the purpose set forth.

11. In a rotary engine, the combination of a shaft, a pair of disks secured to the central portion of said shaft, a pair of valved hollow 120 125 130

piston-members secured to the disks on opposite sides thereof and separated by an angle, a pair of casing sections formed with annular chambers receiving said piston-members and having the ends of said shaft journaled therein and provided with removable top-sections, movable abutments housed in the upper portions of said casing sections, and suitably actuated admission and exhaust valves, for the purpose set forth.

12. In a rotary engine, the combination of a casing having an annular chamber provided on its inner or convex wall with a re-

cess, a valved hollow piston-member movable in said annular chamber and provided at 15 its inner concave wall with an opening registering with said recess in one position of the piston-member, an admission port adjacent to said recess, and suitably actuated admission and exhaust valves, for the purpose set 20 forth.

FREDERICK H. LATHROP.
